Letters Patent No. 1838 dated Nov. 3. 1868.

Design for a Stove plate.

~~~~~

The schedule referred to in these Letters Patent and making part of them.

~~~~~

To all whom it may concern:

Be it known that I,
Robert Ham, of the City of Troy, in the County of
Rensselaer, and State of New York, have invented
or produced a new and original ornamental De-
sign for Stove Plates, and I do hereby declare that
the following is a full and exact description of the
same, reference being had to the annexed photo-
graphic drawing of a stove plate embodying my
said design.

This ornamental design for stove plates
consists of a row of the small ornaments, a, arranged
along the borders of a panel B, surrounded by a panel
C, having a row of the small ornaments, d, arranged
along its border, as shown by the photographic draw-
ing hereto annexed.

What I claim as new and of my inven-
tion or production and desire to secure by Letters
Patent, is, a stove plate having rows of the ornaments
a, and d, arranged along the borders of inner and
outer panels B and C, as herein above described.
